Howes & Gordon

UNITED STATES PATENT OFFICE.

ARCHIBALD B. EDDOWES, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

PISTON.

1,216,218.

specification of Letters Patent. Patented Feb. 13, 1917.

Application filed August 24, 1916. Serial No. 116,653.

To all whom it may concern:

Be it known that I, ARCHIBALD B. EDDOWES, a citizen of the United States, residing in Philadelphia, Pennsylvania, have invented certain Improvements in Pistons, of which the following is a specification.

The object of my invention is to securely fasten a bull ring to a piston of a steam or other engine.

10 In the accompanying drawing:—

Figure 1, is a transverse sectional view of a piston, illustrating my invention, on the line 1—1, Fig. 2;

Fig. 2, is a face view of the piston;

15 Fig. 3, is an enlarged view of a portion of Fig. 1;

Figs. 4, 5 and 6, are views illustrating a modification of the invention; and

20 Fig. 7, is a view illustrating another modification of the invention.

Referring to the drawing, 1 is the body or the center of the piston, in the present instance made of steel either cast, rolled or forged, and 2 is the bull ring adapted to the 25 periphery of the center and this ring may be made of cast iron, or other suitable material.

On one edge of the center is an annular flange 3 shaped to fit an annular recess in 30 the bull ring 2. The opposite edge of the center has a diagonal groove 4 therein and the ring is beveled on a line with the walls of this groove, as at 5. 6 is an annular ring which is adapted to a recess 4 and rests 35 against the beveled portion of the bull ring forming a flange so that the bull ring is prevented from moving independently of the center by the fixed flange 3 on one side and the locking ring on the opposite side. The 40 ring is a split ring and is forced in position as illustrated in Fig. 1, and, when in this position, the two ends are welded together. The ring is also preferably welded at 7 to the center, making a rigid fastening. The 45 bull ring has the ordinary annular grooves for the packing rings.

In some instances, I may use the construction illustrated in Fig. 7, in which the flange 3^a is undercut and is adapted to fit the undercut portion 8 of the bull ring 2^a, while

at the opposite side there is an undercut portion 9 on the bull ring and a ring 6^a is adapted to fit in this portion of the bull ring and is extended into an annular groove 4^a in the center 1. In order to retain this ring 55 in position, I provide another annular locking ring 6^b, which is sprung into position back of the ring 6^a. The two ends of the ring are welded together and the ring 6^b is welded to the ring 6^a at 7^a. Either one of 60 the rings 6^a or 6^b may be made of a single piece, if found desirable.

In Figs. 4, 5 and 6 is illustrated a further modification in which a ring 6^c is used having an annular tongue 6^d. The ring is 65 adapted to an annular recess 5^a in the bull ring 2^c, while the tongue is adapted to an annular recess in the center 1, and, when the two parts are assembled, the ring can be forced into position, as in Fig. 4. I make 70 the abutting ends of this ring as illustrated in Fig. 6, one beveled end of the ring overlapping the other and one of the ends forms a recess so that the parts can be welded, as at 7^b. In some instances, in addition to the 75 locking ring, one or more pins 10 may be used to retain the two parts in position.

By this construction, I am enabled to firmly secure the bull ring to the center, the ring being held on one side by an annular 80 flange formed integral with the center, while at the opposite side an annular flange is formed by the locking ring, which is firmly held in position. No bolts, or other devices, are used which project beyond the piston, 85 making a very compact and simple piston construction.

I claim:—

1. The combination in a piston, of a center having an annular flange at one edge 90 and having an annular groove at the opposite edge; a bull ring mounted on the piston and having an annular groove alining with the groove in the center; and a locking ring adapted to both grooves. 95

2. The combination in a piston, of a center having an annular flange at one edge and having an annular groove at the opposite edge; a bull ring mounted on the piston and having an annular groove alining 100

with the groove in the center; a locking ring adapted to both grooves; and means for securing the locking ring to the center.

3. The combination in a piston, of a center having an annular flange at one edge and having a diagonal, annular groove at the opposite edge; a bull ring recessed at one edge

to receive the annular flange of the center and beveled on a line with the inclined groove; and a locking ring adapted to the 10 groove and extending against the beveled portion of the bull ring, securing the bull ring firmly to the center.

ARCHIBALD B. EDDOWES.
